UNITED STATES PATENT OFFICE

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY

LOOPER-THREAD-CONTROLLING MECHANISM FOR SEWING MACHINES

Original application filed January 28, 1928, Serial No. 250,111. Divided and this application filed October 12, 1928. Serial No. 312,012.

This invention relates to sewing machines of the cylinder-bed chain-stitch type and has for an object to provide a sewing machine with simplified and compact looper-thread controlling mechanism particularly adapted to be housed in the restricted space within the cylinder-bed.

The looper-thread controlling mechanism comprises a crank-and-link take-up device disposed within and preferably crosswise of the cylinder-bed, at the end of the main-shaft, and between the latter and the two slotted arms of the feed-and-return actuating mechanism. The anchor-link of the take-up is loosely carried by the feed-lift rock-shaft.

The invention will be better understood by referring to the accompanying drawings in which Fig. 1 is a horizontal section through the cylinder-bed and standard of the machine. Fig. 2 is a sectional view on the line 2—2, Fig. 1, and Fig. 3 is a perspective view of the looper-thread-controller actuating crank.

In the preferred embodiment of the invention illustrated, 1 represents the standard of the sewing machine which carries a cylinder-bed 2 in which is journaled in the bearings 3, 4 and 5, the main-shaft 6.

The looper-thread controlling-mechanism comprises a crank-and-link take-up mounted within and crosswise of the cylinder-bed at the end of the main-shaft 6. Fixed to the main-shaft is the circular head 7 carrying the crank-pin 8 which is embraced by one end of the lever-arm 9 fulcrumed at 10 to one end of the anchor-link 11 journaled freely on the feed rock-shaft 12. The lever 9 is provided with spaced sockets 13 in which are fitted the thread-arms 14 having in their free ends the thread-eyes 15. Between the arms 14 is mounted on the bearing-lug 16 the fixed thread-guide 17. At the rear of the rearwardly disposed take-up arm 14 is mounted a second fixed thread-guide 18.

When the loopers 19 are fully advanced, the movable thread-eyes 15 are in substantial alinement with the thread-eyes in the fixed guides 17 and 18. As the loopers retract, the movement of the thread-eyes 15, toward their

dotted line position, Fig. 2, takes up the slack looper-thread. The return movement of the thread-eyes 15 to their full line position, Fig. 2, gives up thread to the loopers in their movement to the end of their advancing stroke.

The actuating mechanism for the loopers 19 may be of any desired construction. I prefer to use, that disclosed in my copending application, Serial No. 250,111, filed January 28, 1928, of which this application is a division. The loopers 19 cooperate as usual with the reciprocating needles 20.

The feed rock-shaft 12 is actuated by the crank 21 and link connection 22 with the eccentric 23 on the main-shaft 6, as disclosed in my said copending application.

Having thus set forth the nature of the invention, what I claim herein is:—

1. The combination with a sewing machine having a cylinder-bed, a reciprocating needle, and a thread-carrying looper, of a looper-thread controller including a crank-operated take-up lever and anchor-link housed entirely within said cylinder-bed and constructed to take-up and pay out looper-thread in timed relation with the retraction and advance of the looper.

2. A sewing machine having, in combination, a frame including a standard, a bracket-arm, and a cylinder-bed, a main-shaft journaled in said frame lengthwise of and extending into the cylinder-bed, a crank on the end of the main-shaft within the cylinder-bed, a reciprocating needle, a thread-carrying looper, a looper-thread take-up lever connected to said crank, and an anchor-link connected at one end to said lever and at its opposite end to a fixed point within the cylinder-bed.

3. A sewing machine having, in combination, a frame including a standard, a bracket-arm, and a cylinder-bed, a reciprocating needle, a thread-carrying looper, and looper-thread controlling mechanism including a crank-and-link take-up housed within said cylinder-bed and performing its movements in parallel planes transversely of the cylinder-bed.

4. A sewing machine having, in combination, a frame including a standard, a bracket-

arm, and a cylinder-bed, a reciprocating needle, a thread-carrying looper, a feed rock-shaft journaled within and lengthwise of the cylinder-bed, a main-shaft journaled in said frame lengthwise of and extending into said cylinder-bed, a crank on said main-shaft, a looper-thread-controlling lever connected to said crank, and an anchor-link freely connected at one end to said feed rock-shaft and at its other end to said looper-thread-controlling lever.

In testimony whereof, I have signed my name to this specification.

ANDREW B. CLAYTON.
